UNITED STATES PATENT OFFICE.

EDMUND RUSSELL, OF BROOKLYN, NEW YORK.

IMPROVEMENT IN STEAM-HEATERS.

Specification forming part of Letters Patent No. **138,200**, dated April 22, 1873; application filed January 22, 1873.

To all whom it may concern:

Be it known that I, EDMUND RUSSELL, of Brooklyn, in the county of Kings, State of New York, have invented certain Improvements relating to Steam-Heaters, of which the following is a specification:

The novelty lies in the construction of the radiators. They are screwed into a base like ordinary tubes. Instead of being plain tubes they are peculiarly duplicated and chambered to facilitate the circulation of the steam and the expulsion of the air.

The following is a description of what I consider the best means of carrying out the invention.

The accompanying drawing forms a part of this specification.

Figure 1 is a front view, partly in section, and Fig. 2 is a cross-section of the base with a vertical section through a radiator.

Similar letters of reference indicate like parts in both figures.

The radiators are each a single casting. For convenience of description I will apply the marks A^1 , A^2 , &c., to the different parts of the radiator, and the simple letter A to indicate the whole, if necessary. B is the base, formed and connected to a steam-boiler as usual by pipes. The neck A^1 of my radiator is tapped into the base B . Above are two upright branches, A^2 A^3 , connected at several different levels by cross-channels A^4 , A^5 , &c. The cross-connection at the top is surmounted by an ornamental plug, C , which stops the hole usually necessary in producing the casting.

I make the interior of the casting hollow by coring. It involves no skill beyond that ordinarily possessed by founders.

The neck A^1 is formed with a deflection to one side at its junction with the two branches A^2 A^3 , so that on admitting steam to the ap-

paratus it is thrown forcibly to one side and caused to rise in the branch A^2 , while the air in both branches is allowed to descend through the branch A^3 , traversing across to get into A^3 , through either of the cross-connections A^4 , A^5 , &c.

Inertia and friction tend to resist the motion of fluids in starting from rest in long tubes. It requires less force to start the current in short lengths of the branches than in the whole branches at once. When the steam is first introduced it rises in the branch A^2 only to the first cross-connection A^4 ; there it crosses to the branch A^3 and descends. After establishing a current in this lower part of the branches the impact of the rising current in the branch A^2 tends to constantly force upward the air in the same branch above, while the down current in the lower part of the branch A^3 makes it easy for the air on that side to be gradually mixed and drawn down. Soon the current commences to cross in the cross-connection A^5 , and ultimately in the top connection whatever may be its height.

I claim as my invention is—

1. The cross-connections A^4 , A^5 , &c., arranged, as shown, at different levels between the branches A^2 A^3 and adapted to allow the steam to circulate first in a short length and afterward in a longer length of the radiator, as herein specified.

2. The within-described construction and arrangement of all the parts A^1 , A^2 , A^3 , A^4 , A^5 , &c., when formed in a single casting, as herein set forth and described.

In testimony whereof I have hereunto set my hand this 17th day of January, 1873, in the presence of two subscribing witnesses.

EDMUND RUSSELL.
